DESIGN FOR A PANELED DOLL OR SIMILAR ARTICLE

Rachel E. Phillips, Cleveland, Ohio

Application September 21, 1940, Serial No. 95,260

Term of patent 7 years

To all whom it may concern:

Be it known that I, Rachel E. Phillips, a citizen of the United States of America, residing at Cleveland, in the county of Cuyahoga and State of Ohio, have invented a new, original, and ornamental Design for a Paneled Doll or Similar Article, of which the following is a specification, reference being had to the accompanying drawing, forming a part thereof, in which:

Figs. 1 and 2 are respectively perspective views of the paneled doll showing my new design.

I claim:

The ornamental design for a paneled doll or similar article, substantially as shown.

RACHEL E. PHILLIPS.
